US00D794153S

(12) **United States Design Patent** (10) **Patent No.:** **US D794,153 S**
(45) **Date of Patent:** **** Aug. 8, 2017**

(54) **FIREARM TRIGGER**

(71) Applicants: **John Capps**, Maricopa, AZ (US);
Frank DeSomma, Glendale, AZ (US)

2,102,622 A 12/1937 Green
2,110,165 A 3/1938 Moore
2,116,141 A 5/1938 Browning
(Continued)

(72) Inventors: **John Capps**, Maricopa, AZ (US);
Frank DeSomma, Glendale, AZ (US)

OTHER PUBLICATIONS

(73) Assignee: **PATRIOT ORDNANCE FACTORY, INC.**, Phoenix, AZ (US)

USPTO; Non-Final Office Action dated Nov. 24, 2010 in U.S. Appl. No. 12/489,592.

(Continued)

(**) Term: **15 Years**

Primary Examiner — Michael A Pratt

(21) Appl. No.: **29/551,237**

(74) Attorney, Agent, or Firm — Snell & Wilmer, L.L.P.

(22) Filed: **Jan. 12, 2016**

(57) **CLAIM**

The ornamental design for the firearm trigger, as shown and described.

DESCRIPTION

FIG. 1 is a first perspective view depicting an embodiment of a new design for a firearm trigger;

FIG. 2 is a second perspective view depicting an embodiment of a new design for a firearm trigger;

FIG. 3 is a side view depicting an embodiment of a new design for a firearm trigger;

FIG. 4 is a side view depicting an embodiment of a new design for a firearm trigger;

FIG. 5 is a front view depicting an embodiment of a new design for a firearm trigger;

FIG. 6 is a rear view depicting an embodiment of a new design for a firearm trigger;

FIG. 7 is a bottom view depicting an embodiment of a new design for a firearm trigger;

FIG. 8 is a top view depicting an embodiment of a new design for a firearm trigger; and,

FIG. 9 is a side view depicting an embodiment of a new design of a firearm trigger installed in an exemplary firearm. The portion shown in broken line is for illustrative purposes only and forms no part of the claim design.

1 Claim, 5 Drawing Sheets
